CORNICE MOUNTING FOR SHOWER CURTAINS
Harold Grossman, 4723 N. Pulaski Road, Chicago, Ill.
Filed Mar. 10, 1965, Ser. No. 438,523
3 Claims. (Cl. 248—264)

This invention relates to a cornice mounting for showerbath curtains.

The main objects of this invention are; to provide an entirely new structure of a mounting for shower curtains used with conventional bath tubs, shower stalls etc.; to provide a mounting of this kind with an improved form of traverse bar and anchoring means for detachably supporting the bar on the end walls defining the tub area; to provide an improved cornice mounting of this kind which permits of an aesthetic formation of all exposed faces thereof; and to provide an improved ornamental mounting of this kind of such simple structure as to make very economical its manufacture and marketing, most facile and secure the mounting thereof on the walls, and permit a wide range of ornamental formation of its exposed faces so as to accord it a preference over all other types of shower-curtain mountings otherwise available.

In the adaption shown in the accompanying drawings:

FIGURE 1 is a miniature front view of a conventional bathtub with a shower-curtain suspended from a cornice mounting constructed in accordance with this invention;

FIG. 2 is an enlarged top view of the end portion of this improved cornice mounting within the circle "A" of FIG. 1;

FIG. 3 is an enlarged front view of the assembly shown in FIG. 1 with part broken away to indicate the provision for the curtain-suspension hooks;

FIG. 4 is a reduced-size, transverse, sectional view taken on the plane of the line 4—4 of FIG. 3;

FIG. 5 is a reduced-size, transverse, sectional view taken on the plane of the line 5—5 of FIG. 3;

FIG. 6 is an exploded view of one end of this five-part structure, preparatory to securing the mounting in use position, and

FIG. 7 is a front view with the traverse bar and wall bracket set to permit the anchor member to be shifted into place to lock the traverse bar in curtain suspending position on the wall bracket.

The essential concept of this invention involves an ornamental, front-face traverse bar, the ends of which are secured to a pair of angle brackets by means of comparably-ornate, slidably-supported anchoring members.

A shower-curtain mounting embodying the foregoing concept comprises a traverse bar 11, a pair of identical anchoring members 12 and a pair of supporting wall-brackets 13 in the form of right angle bars.

The traverse bar 11, as here shown, is channel-shaped with front and rear transverse parts 14 and 15, respectively, extending parallel downwardly from a base part 16. The length of the traverse bar 11 is just enough to fit conveniently between the end walls W-1 and W-2, which define the ends of the bathtub area, and permit easy but secure support of the bar 11 on the L-shaped wall brackets 13, as will be explained.

The front face of the bar part 14 here is shown formed with a Doric style ornamentation. Thus, the upper and lower portions 17 and 18 of the bar 11 are slightly concave thereby forming pairs of longitudinal ridges 19 along the top and bottom margins of the bar 11. Obviously, other types of ornamentation may be employed with equal aesthetic appeal. The transverse parts 14 and 15 extend slightly above the base 16 to form rims 21 and 22, respectively, (FIG. 4). These are of a height substantially equal to the thickness of the metal from which the brackets 13 are formed. Thus, these rims 21 and 22

2

define a seat 23 (FIG. 7) for the horizontally-disposed legs 24 of the brackets 13, as will be explained.

Interiorly, along the juncture of the rear transverse part 15 and the base 16, of the bar 11, a channel 34 is formed for the traveling support of the conventional hooks 25 whereon is suspended a shower curtain 26. At each end of the channel is secured a bolt-and-nut stop 20 to retain the hooks 25 against inadvertent displacement from the channel 34.

10 The pair of identically-formed anchoring members 12 are channel-shaped very much in the cross-sectional contour of the bar 11. The front and rear parts 27 and 28 extend transversely of a base 29. They have their respective extremities shaped to form rails 30 and 31 embracing the lower edges of the transverse parts 14 and 15 of the bar 11. Thus, these anchoring members 12 are free to slide along the bar 11 when they are inserted over the one or the other ends thereof. The front face of each of these anchoring members 12 is ornamented to conform with the above-described Doric style of the front face of the bar 11.

15 A set screw 32 is positioned medially of the base 29 of each of these members 12. This permits securing the members 12 to the ends of the bar 11 with the legs 24 of the brackets 13 embraced in seats 23 of the bar 11 (see FIG. 7).

20 The brackets 13 are sections of conventional angle bar. In use these brackets are secured to the walls W-1 and W-2 in any known manner such as by screws 33 with the legs 24 in opposed horizontal alignment.

25 The five elements of the above-described shower-curtain cornice mounting arrive disassembled at a showerbath installation. It remains only to cut the traverse bar 11, to an appropriate length, in the event it is longer than the distance between the walls W-1 and W-2.

30 Thereupon, the brackets 13 are anchored to the respective walls W-1 and W-2, at the desired height and with the legs 24 in opposed horizontal alignment.

35 The anchoring members 12, with the set screws 32 retracted, are set over the respective ends of the bar 11, a distance inwardly greater than the length of the legs 24 of the brackets 13. The bar 11 then is positioned with the ends set up against the under face of bracket legs 24 to position them in the seats 23 at the ends of bar 11 (FIGS. 6 and 7).

40 The anchoring members 12 then are shifted outwardly along the bar 11 to position them over the overlapping legs 24 of the brackets 13 (FIG. 3). Tightening of the set screws 32 now fixes the unit solidly in position.

45 The cornice-mounting, thereupon, is ready to have the shower-curtain attached to the series of hooks 25, in the usual manner.

50 Although but one specific embodiment of this invention is herein shown and described, it will be understood that details of the construction shown may be altered or omitted without departing from the spirit of the invention as defined by the following claims.

I claim:

55 1. A cornice-mounting for shower-bath curtains comprising a traverse bar channel-shaped in cross section with parallel parts disposed transversely of the base for inverted horizontal disposition between the walls defining a bath area to provide a raceway for shower-curtain suspension means and having an ornate, vertically-disposed front face, a pair of wall brackets L-shaped in cross-section for inverted positioning with one leg attached to a wall to dispose the other leg horizontally, the long leg being of a width less than the width of the base part of the bar, a pair of anchoring members channel-shaped in cross-section with parallel parts disposed transversely of

the base and slidably supported in inverted positions on the bar, having an ornate front face to match the front face of the bar, and oppositely shiftable along the bar into positions embracive of the overlapping end portions of the bar base and the other leg of the respective brackets to secure the bar in curtain-suspension position, and means on each anchoring member for keying the members in use position on the bar.

2. A cornice-mounting for shower-bath curtains as set forth in claim 1 wherein the transverse parts of the bar have inwardly extending short portions spaced from the base of the bar to define a seat of a depth substantially equal to the thickness of the material from which the brackets are formed and wherein the one leg of each bracket is embraced by the respective member.

3. A cornice-mounting for shower-bath curtains as set forth in claim 2 wherein the parallel parts of the anchoring members have terminal rails embracing the edges of the respective transverse parts of the bar.
